UNITED STATES PATENT OFFICE.

ALBERT E. GRANT, OF NEW YORK, N. Y., ASSIGNOR, BY MESNE ASSIGNMENTS, TO GRANT INVENTIONS COMPANY, INC., OF WILMINGTON, DELAWARE, A CORPORATION OF DELAWARE.

LIQUID-FUEL APPARATUS.

Application filed September 18, 1924. Serial No. 738,433.

My invention relates to apparatus for preparing oil for combustion.

The objects of my invention are to provide a simple and reliable apparatus for mixing oil and air to provide a fuel, and deliver said fuel in atomized condition to a furnace.

The detailed construction of my apparatus is illustrated in the drawings forming a part of this specification.

Fig. 1 is a front elevational view, shown partly in section, of the pumps and mixing chamber in which the oil and air is mixed, and of the oil cistern or sump from which the oil is drawn.

Fig. 2 is an end view corresponding to Fig. 1.

Fig. 3 is a view of the pump for oil taken on line 3—3 of Fig. 1.

Fig. 4 is a cross sectional view taken on line 4—4 of Fig. 1.

Fig. 5 is a cross sectional view taken on line 5—5 of Fig. 1 and

Fig. 6 is a diagrammatic view illustrating the piping arrangement and further detailed construction.

A, indicates a casing having a cistern or sump A' therein. Mounted on the top of the casing A, is a pump B, of the positive pressure type, constructed similar in its principle of operation to the well known "Root blower".

This pump comprises two rotors or impellers C, C, respectively, each mounted on a separate shaft D, D, respectively, which shafts are supported in bearings D', D', D', and are automatically lubricated by a portion of the oil being pumped, as will herein-after be explained.

The shafts D, D, are geared together as illustrated in Fig. 3 by gears E, E, enclosed in casing E² and are so constructed as to serve as pumps Z, and Z', to control the oil flow to and from the cistern A'. The construction of these gear pumps will be easily understood by reference to Figures 1, 3, and 5, in which it is seen that the two co-acting gear wheels E, E, are mounted on the shafts D, D, the latter being driven by a motor F, to which one of said shafts is connected by a coupling F'. The outer surfaces of the teeth E' of gears E, are arranged to move in close proximity to the circular inner

walls B', B', of the casing E², and are in close mesh at B', so that oil is led into the sump thru the pipes M, G and M² respectively, between the teeth E', the oil from pump Z, flowing into the sump thru pipe G; and the excess oil being drawn from the sump by pump Z', thru pipe G', is discharged thru pipe N, back to the supply reservoir L.

The present construction comprises three pumps including the pump B, in the mixing chamber, each pump comprising two members mounted on oppositely disposed shafts, the gears of the oil pumps serving to drive the mixing pump B, in timed relation with the oil pumps, and the pump Z' serving to maintain a constant oil level in the sump.

The pump casing Z² and Z' of the pumps Z and Z' respectively, may be bolted to the main casing of the mixing chamber as illustrated and are separable therefrom so that the gears E, may be inspected and be replaced without difficulty.

H, indicates an air inlet to the sump chamber which is controlled by a valve construction of any desired type, the most simple being such as is used in gas ranges and known as a "butterfly" valve, which construction is well known to this art. The casing B² is provided with air intake passages I, I, in open communication with sump A' and with the outlet end of an oil supply pipe J, which extends from near the bottom of the sump chamber to the inner surface of the mixing chamber B, between said air passages I, I, and adjacent thereto.

An outlet pipe K, leads the fuel mixture from the mixing chamber B³ to a burner or furnace for use.

The main oil reservoir L, which may be located above the level of the sump A', has a delivery pipe M, extending upwardly from near the bottom thereof and thence to the inlet of pump Z, and therethru upwardly to the outlet at M' to a standpipe M² of slightly larger diameter than that of pipe M.

The pipe M² has an upwardly extending portion above the point M' which is open to the atmosphere at M³.

The pipes, G' and J, are preferably made adjustable in length so that their lower ends may be set at various levels in the

chamber A' for the purposes hereinafter described.

Pipes G² respectively, extend from end chambers formed in the casing adjacent the oil pumps Z and Z' to lead any surplus oil flowing thru the bearings to lubricate the same, into the oil sump chamber.

The operation of the apparatus is as follows:

- 10 The motor F, is started and pump Z draws oil from the reservoir L, and forces it thru pipe G into the stand pipe at M' whence it flows by gravity downward thru pipe M² into the sump chamber, the upper end of 75
15 the pipe M² extending above the point M' being open to the atmosphere at M³, and serving to prevent syphoning of oil or seepage thru the pump which might occur if the outlet from the mixing chamber of pump B, 80
20 was below the oil level in the reservoir L due to a vacuum having been formed in said mixing chamber. It is obvious however, that the apparatus would operate if the opening at M³ was closed, but the oil would 85
25 not flow downward in said pipe M² by gravity alone, but would be directly forced downward into the sump chamber.

A portion of the oil is drawn from the sump into the mixing chamber B², together 90
30 with a predetermined quantity of air which has been admitted to the sump chamber thru the valve controlled inlet H, and with a quantity of the foam from the surface of the oil which is generated by the agitation 95
35 of the incoming oil from the pump Z and air, and is carried with the air into the mixing chamber, together with the oil which is drawn by the pump B, into the mixing chamber and spread laterally and mixed with the 100
40 air and practically churned to provide a proper fuel mixture, the impellers C, C, serving to perform this function, and acting as a pump to force the fuel thru the pipe K to a burner or other place for use. The 105
45 capacity of the oil pump Z' is equal to or exceeds that of the pump Z. The height of the oil in the sump A' is controlled by adjusting the position of the lower end of the suction pipe G'.

50 The oil passing thru the pumps Z and Z' is carried to the bearings D', D', D', along the shafts D, D, and serves to lubricate said bearings, the surplus oil therefrom passing thru the adjacent chambers opening into the pipes G², and thru said pipes into the sump, thus dispensing with packing glands on shafts D. This lubrication is facilitated by the reduction of the atmospheric 115
55 pressure in the sump A' during the operation of the pump B, which causes the oil to be drawn thru the bearings, as will be readily understood.

Where the reservoir L is located below the 120
60 level of the sump A', the oil may be drawn therefrom and delivered directly into said 125
65 sump by the pump Z, and returned thereto by the pump Z', and the upper end of the stand pipe either closed, or removed altogether, and the oil pumped directly into the sump. The sump casing serves as a 70
75 base for the pumps which are mounted on the top thereof, the lower part of the casing of the mixing chamber serving to close the top opening thru which the pipe J extends, and permitting the air passages I, to be located directly above the oil level in the sump and exposed thereto so that the frothy oil and air can be easily carried thru the passages I, directly into the mixing chamber.

The amount of oil delivered to the mixing 80
pump B, is dependent upon and controlled by the valve governing the inlet passage H which controls the amount of air admitted to the sump chamber.

The parts are so adjusted that if the air 85
valve is wide open, no oil will be drawn by the pump B into the mixing chamber, because the depression in the said mixing chamber will be insufficient to raise the fuel, but by limiting the air supply, the oil will 90
be drawn into the pump with the required amount of air to provide the desired fuel mixture, and this mixture is made complete by the "Root" type of pump or blower employed for this purpose, since it has been demonstrated that the impellers in their rotation do mix the air and oil into a more atomized condition than can be obtained by a single blade construction pump. On the other hand if the air valve is closed too 95
100 much, the air pressure in the sump and mixing chamber will be equalized and no fuel will be drawn into the mixing chamber. This result is brought about because what causes the rise of fuel in pipe J is the difference in the pressures existing between the sump chamber and mixing chamber and such pressures depend on the amount of air admitted.

Having thus described my invention, I 110
claim as new:

1. A liquid fuel apparatus comprising a closed sump chamber, adjustable means for controlling the admission of air to said chamber, a pump having a mixing chamber located above said sump chamber and having independent passages for air and oil leading from said sump chamber thereto, said adjustable means serving to also control the pressure effective on the fuel level in said sump chamber, and a pump for maintaining the fuel in said sump chamber at a predetermined level.

2. A liquid fuel apparatus comprising a sump chamber having air inlet means there- 125
to, means for delivering fuel to said chamber, a pump of the Root blower type located above said chamber and having independent passages for air and oil leading from said sump chamber thereto, adjustable means for 130

- controlling the volume of air flowing through said air inlet means, and a pump for returning a portion of the fuel from said sump chamber to a source of supply and serving to maintain the fuel at a predetermined height in said chamber, said adjustable means serving to also control the pressure effective on the fuel level in said sump chamber.
- 10 3. A liquid fuel apparatus comprising a sump chamber, a pump for delivering fuel to said chamber, a valve for controlling the admission of air to said chamber, a pump of the Root blower type located above said chamber and having independent passages for air and oil leading from said sump chamber thereto, a pump for returning a portion of the fuel from said sump chamber to a source of supply and means for operating said pump in synchronous relation to thus maintain a constant level of the fuel in said sump chamber, said valve serving to also control the pressure effective on the fuel level in said sump chamber.
- 15 4. A liquid fuel apparatus comprising a sump chamber, a valve for controlling the admission of air thereto, means for delivering fuel to said chamber, a pump having a mixing chamber located above the sump chamber and having independent passages for fuel and air leading from said sump chamber thereto with their outlets located adjacent to each other within said mixing chamber, means for returning a portion of said fuel from the sump chamber to a source of supply, and means for operating said pumps in synchronous relation to thus maintain a constant level of the fuel in said sump chamber, said valve serving to also control the pressure effective on the fuel level in said sump chamber.
- 20 5. A liquid fuel apparatus comprising a sump chamber, a pump for delivering fuel to said chamber, a pump for mixing and delivering atomized fuel to an outlet, said pumps being located above said chamber, and having separate inlet passages for air and oil, the outlets of which are located adjacent to each other in said mixing chamber, said pump comprising a pair of impellers of the Root blower type, said mixing chamber having an outlet of restricted area, a second pump in communication with the sump chamber for returning the excess fuel to a source of supply, all of said pumps being driven in synchronism, and means for adjustably controlling the admission of air to said sump chamber whereby the pressure effective in said sump chamber is controlled.
- 25 6. A liquid fuel apparatus comprising a closed sump chamber, a valve for controlling the admission of air into said chamber and serving to also control the pressure effective on the fuel level therein, a mixing pump located above said sump chamber and in communication therewith, and drawing its air supply thru said valve and its fuel supply from said sump chamber, operating means for said pump including a plurality of gearing means, said gearing means also serving as two pumps, one adapted to deliver fuel into said sump chamber and the other to return fuel from said sump chamber whereby a constant level of fuel is maintained in said sump chamber.
- 30 7. A liquid fuel apparatus comprising a closed sump chamber, a feed pump having impellers located above the sump chamber and in open communication therewith, a fuel delivering pump and a return delivery pump, each having conduits in communication with the sump chamber, said feed pump being adapted to mix the air and fuel therein to provide an atomized mixture, said feed pump having an outlet of restricted area relative to the inlet areas thereto, said return pump operating to maintain a predetermined level of fuel in said sump chamber, all of said pumps being driven in synchronous relation, and adjustable means for controlling the admission of air to said sump chamber, said adjustable means serving to also control the pressure effective on the fuel level in said sump chamber.
- 35 8. A liquid fuel apparatus comprising a sump chamber, a valve for governing the flow of air to said chamber, a feed pump located above said chamber in open communication therewith, said feed pump having impellers adapted to mix air and fuel therein to provide an atomized mixture, and having an outlet of reduced area relative to the inlet area thereto, a supply pump and a return pump communicating with said sump chamber and with the source of supply, a main shaft common to all of said pumps, said supply and return pumps being substantially of the same capacity, and said valve serving to also control the pressure effective on the fuel level in said sump chamber.
- 40 9. A liquid fuel apparatus comprising a sump chamber, a valve for admitting air to said chamber, a feed pump located above said chamber in open communication therewith, a supply pump and a return pump communicating with said chamber and a source of fuel supply, a main shaft common to all of said pumps, bearings for said shaft located adjacent to said supply and return pumps, the arrangement being such that the bearings are lubricated by oil supplied to said pumps, and means for returning oil from the bearings to said sump chamber, said valve serving to also control the pressure effective on the fuel level in said sump chamber.
- 45 10. A liquid fuel apparatus comprising a sump chamber, means for drawing oil from a source of supply and delivering same to

said chamber, a valve for controlling the flow of air to said chamber, means for withdrawing oil from said sump chamber to maintain a constant oil level therein, and a feed pump for drawing air and oil from said chamber, the proportions of air and oil being controlled by the volume of air admitted to

said chamber, said valve serving to also control the pressure effective on the fuel level in said sump chamber.

In testimony whereof I have affixed my signature.

10
